METHOD AND APPARATUS FOR TEMPERATURE REGULATION

Martin Frisch, New York, N. Y., assignor to Foster Wheeler Corporation, New York, N. Y., a corporation of New York

Application October 11, 1940, Serial No. 360,825

9 Claims. (Cl. 122—479)

This invention relates to temperature regulation, and more particularly pertains to the control of the temperature of superheated vapor.

In accordance with the invention, the temperature of the superheated vapor is controlled by varying the amount of moisture present in the vapor at the superheater inlet. This is accomplished by condensing a portion of the purified vapor before its admission to the superheater. The mixture of the condensed and uncondensed vapor thus produced is delivered to the superheater and a part of the heat input to the superheater is utilized to evaporate the condensed vapor. Thus the final vapor temperature may be controlled, or it may be maintained constant, under varying loads imposed on the generator, by controlling the amount of condensed vapor delivered to the superheater.

The invention will be disclosed as applied to the control of temperature of superheated steam, but it will be understood that the invention is capable of application to the temperature control of vapors generally.

Heretofore, the temperature of superheated steam has been controlled by injecting feed water into the superheater, but since all feed water contains considerable amounts of impurities, the injection of such water has always been considered undesirable because some of the solids in the water are left in the superheater on evaporation and eventually cause damage because of the formation of scale on the inner surfaces of the superheater tubes which results in overheating of the tubes. The remaining solids which go through the superheater may cause valves and turbines to foul causing outage and loss of capacity. With the present invention the water introduced to the superheater does not come from an outside source, but is condensed steam normally flowing to the superheater from the steam source. Consequently, this water is chemically pure and does not carry into the superheater tubes any additional solids or impurities which would ordinarily be present in feed water.

The invention will be understood from the following description when considered in connection with the accompanying drawing in which the single figure is a more or less diagrammatic representation of a steam generator, in partial vertical section, embodying a preferred form of the invention.

Referring to the drawing, a main upper steam and water drum 10 is connected to another upper drum 11 by a group of water circulator tubes

12 and by a group of steam circulator tubes 13. Steam generating tubes 14 are connected at their upper ends to the drum 10, and steam generating tubes 15 are connected to the drum 11. Although not shown in the drawing, it will be understood that the steam generating tubes are suitably connected at their lower ends in the circulatory system of the unit, which also includes the necessary downcomer tubes, not shown. Feed water is introduced to the drum 10 through a feed water distributing pipe 16 which is connected with feed line 17. In the form shown, steam purifying devices such as a steam washer 18 and a drier 18', are disposed within the steam space of the drum 10. A superheater 19 which is provided with inlet and outlet headers 20 and 21 respectively, is positioned within a gas pass or heating zone which is bounded in part by the groups of steam generating tubes 14 and 15, and the circulating tubes 12, in the form shown. Saturated steam after having been purified by the devices 18 and 18' is conducted from the drum 10 to the superheater inlet header 20 by steam line 22. Within the header 20 is a condensing coil 23 which is supplied with cooling water through line 24 which is joined with the feed water inlet line 17 by a T-connection 25. The cooling water leaves the coil 23 and flows to the drum 10 through elbow 26 and T-connection 27 in the line 17. Superheated steam is discharged from the outlet header 21 and is conducted to a point of use by conduit 28.

Disposed within conduit 28 is a steam temperature measuring device 29 of any suitable type, such as a thermostat, which is connected by line 30 to a temperature regulating device or controller, presently to be described. A feed water regulating valve 32 is operated in response to the saturated steam output through a differential pressure responsive controller 55 having a diaphragm 56 which is urged downwardly, as shown by a coil spring 57. Opposite sides of the diaphragm 56 are connected to opposite sides of an orifice 58 in steam line 22, by conduits 59 and 60. Diaphragm 56 operates a rod 61 which is connected through a link 62 to a lever 63 one end of which is pivoted to a fixed point and the other end of which is pivotally connected to one end of a link 64, the other end of which is pivotally connected to a lever 65 which is connected to and operates the valve 32. The valve 32 is arranged, as shown, to open when lever 65 is moved in a clockwise direction and to close upon movement of the lever in the opposite direction. When the steam output increases,

valve 32 will open wider to permit the delivery of a greater quantity of feed water to the drum 10, and when the steam output diminishes, the valve 32 will be moved toward or to closed position to reduce, or cut off, the supply of water to the drum 10. Another feed water regulating valve 51 disposed on the other side of the T-connection 25 from valve 32 in the line 17, is operated in response to variations in the water level in the drum 10, through a float controller 33, the float 34 of which operates a link 35 connected to lever 52 which operates the valve 51. When the water level in the drum 10 falls below the predetermined desired level, the float 34 will open valve 51 or open it wider, and when the water level rises above the predetermined level, the valve 51 will close or will move toward closed position.

Temperature changes in the superheated steam leaving the superheater, are transmitted through line 30 to a Sylphon bellows 38 connected to one end of a lever arm 39 which operates a pilot valve 40. The other end of the lever arm 39 is connected by links 41 and 42 to the rod 43 of a piston 44 which moves in a relay cylinder 45. A fluid such as oil, which normally fills the relay cylinder, is led to pilot valve 40 through a feed tube 46 and is permitted to flow from the valve either through tube 47 to the upper portion of the relay cylinder above the piston, or through tube 48 to the lower portion of the cylinder, the different paths of flow being controlled by the position of the valve 40. A flow regulating valve 49 in line 24 which conducts cooling water to the condensing coil 23, is connected to piston rod 43 through a lever arm 50.

In operation, steam entering the drum 10 will be purified by passing through the steam washer 18 and the drier 18' and will be conducted through line 22 to the header 20 wherein it will pass over the condenser 23, and part of the steam will be condensed by indirect contact with feed water flowing to the condenser through pipe 24. The mixture of steam and substantially all of the condensate will flow into the superheater elements 19. Part of the heat input to the superheater is utilized to evaporate the condensed steam flowing into the superheater, so that the final steam temperature may thereby be controlled. The amount of steam condensed in the header 20 is controlled by controlling the amount of feed water that is passed through the condenser 23 in response to the temperature of the steam flowing from the superheater. When the temperature of the steam leaving the superheater outlet header 21 exceeds a predetermined value, the temperature measuring device 29 causes the Sylphon 38 to expand downwardly to connect the oil flow path 48 with the feed tube 46 and to connect the flow path 47 with the valve discharge. This changes the balance in the relay cylinder 45 with the result that the piston 44 and rod 43 will move upwardly, thereby opening the valve 49. An additional amount of cooling water then will flow to the condensing coil 23, and a greater amount of steam will be condensed in the superheater inlet header 20, with the result that the final temperature of the superheated steam will be reduced, until the desired steam temperature is attained. If the temperature of the superheated steam falls below the predetermined value, the operation will be reversed, i. e. the temperature controller will operate to close valve 49 or to move it toward closed position, until the temperature of the steam has been increased to the predeter-

mined value. In this way the temperature of the steam is controlled by controlling the amount of steam condensed, and the quantity of steam condensed is varied automatically by varying the amount of water passing through the condenser. During operation, feed water is always available in adequate quantities through line 17, irrespective of variations in load on the generator.

With this arrangement and method, it will be perceived that the desired superheat temperature may be maintained substantially constant automatically during operation of the generator, while at the same time the steam is kept free of solids or impurities additional to those already present in the steam. The temperature measuring device may be set as desired to regulate the temperature of the steam leaving the superheater. This arrangement and method is economical in first cost and in operation, the apparatus is compact, and a minimum heat exchange surface is required because of the relatively high rate of heat transfer from water to condensing steam.

Any suitable type of condenser or condensing equipment may be utilized. Moreover, the invention is not limited in its application to any particular type of steam or vapor generator.

Inasmuch as various changes may be made in the particular form, location and arrangement of the parts of the apparatus disclosed and in the steps of the process and their sequence as disclosed without departing from the principles of the invention, it will be understood that the invention is not to be limited excepting by the scope of the appended claims.

What is claimed is:

1. The method of superheating vapor which comprises passing unsuperheated vapor from a vapor generating zone and without further heat treatment to a condensing zone, condensing part of the unsuperheated vapor in the condensing zone by indirect contact with a condensing medium, introducing the unsuperheated vapor in admixture with substantially all of the condensate produced in the condensing zone into a superheating zone wherein the condensate is vaporized, and controlling the quantity of vapor condensed to control the final temperature of the vapor.

2. The method of superheating vapor which comprises passing saturated vapor from a saturated vapor generating zone and without further heat treatment to a condensing zone, condensing part of the saturated vapor in the condensing zone by indirect contact with a condensing medium, introducing the saturated vapor in admixture with the substantially all of the condensate produced in the condensing zone into a superheating zone wherein the condensate is vaporized, and controlling the quantity of condensing medium brought into contact indirectly with the vapor in the condensing zone in response to the temperature of the vapor after superheating to control the quantity of vapor condensed to thereby control the final temperature of the vapor.

3. The method of superheating vapor in a vapor generator which comprises introducing saturated vapor without further heat treatment into a condensing zone, passing the saturated vapor in indirect heat exchange relationship with feed liquid for the generator in the condensing zone to condense part of the vapor, thereafter passing the saturated vapor in admixture with substantially all of the condensate produced in the condensing zone through a superheating zone wherein the condensate is vaporized, and controlling the quantity of feed water passed through the condensing

zone to control the final temperature of the vapor.

4. The method of superheating vapor in a vapor generator which comprises introducing saturated vapor without further heat treatment into a condensing zone, passing the saturated vapor in indirect heat exchange relationship with feed liquid for the generator in the condensing zone to condense part of the vapor, thereafter passing the saturated vapor in admixture with substantially all of the condensate produced in the condensing zone through a superheating zone wherein the condensate is vaporized, and controlling the quantity of feed water passed through the condensing zone in response to the temperature of the vapor after superheating to control the final temperature of the vapor.

5. Apparatus for superheating vapor comprising a superheater, means for heating the superheater, a condenser, means for supplying a cooling medium to the condenser, means for passing unsuperheated vapors from a vapor generator and out of heat exchange relationship with a heating medium to the condenser and in heat exchange relationship with the condenser to condense part of the vapor prior to superheating, means for introducing the unsuperheated vapor in admixture with substantially all of the condensate produced in the condenser into the superheater, and means for controlling the quantity of vapor condensed.

6. Apparatus for superheating vapor comprising a superheater having tubular members, means for heating the superheater, a condenser having a condensate outlet, means for supplying a cooling medium to the condenser, means for passing unsuperheated vapor from a vapor generator and out of heat exchange relationship with a heating medium to the condenser and in heat exchange relationship therewith to condense part of the vapor prior to superheating, the tubular members of the superheater being connected to the condensate outlet so that the unsuperheated vapor in admixture with substantially all of the condensate produced by the condenser flows into the tubular members of the superheater, and means for controlling the quantity of vapor condensed in response to the temperature of the vapor after superheating.

7. A vapor generator comprising a vapor generating section, a superheater, a condenser, means for introducing feed liquid for the generator into the condenser, means causing the saturated vapor from the generating section to flow out of heat exchange relationship with a heating medium and into heat exchange relationship with the condenser to condense part of the vapor, means for introducing the saturated vapor in admixture with substantially all of the condensate produced in the condenser into the superheater, and means for controlling the quantity of vapor produced.

8. A vapor generator comprising a vapor generating section, a superheater, a condenser, means for introducing feed liquid for the generator into the condenser, means causing the saturated vapor from the generating section to flow out of heat exchange relationship with a heating medium and into heat exchange relationship with the condenser to condense part of the vapor, means for introducing the saturated vapor in admixture with substantially all of the condensate produced in the condenser into the superheater, and means for controlling the quantity of feed liquid introduced to the condenser in response to the temperature of the vapor after superheating to thereby control the temperature of the superheated vapor.

9. A steam generator comprising a steam generating section including a steam drum, a superheater comprising an inlet and an outlet header and superheater tubes connecting the headers, means for passing steam from the steam drum out of heat exchange relationship with a heating medium to the inlet header, a condenser in the superheater inlet header, means for supplying a condensing medium to the condenser, and means for controlling the quantity of condensing medium supplied to the condenser to control the quantity of steam condensed in the inlet header, the inlets of the superheater tubes communicating with the lower portion of the inlet header so that the steam in admixture with substantially all of the condensate produced by the condenser flows into the superheater to thereby control the temperature to which the steam is superheated.
